CLAIM

I claim the ornamental design for a safety razor, as shown and described.

DESCRIPTION

FIG. 1 is a left side view of a safety razor showing my new design;

FIG. 2 is a right side view of the safety razor;

FIG. 3 is a front view of the safety razor; and,

FIG. 4 is a rear view of the safety razor.

The safety razor is characterized by its surface pattern and overall shape.

The broken lines illustrate a portion of the safety razor and form no part of the claimed design.
